UNITED STATES PATENT OFFICE.

FREDERICK S. BATCHELLER, OF PROVIDENCE, RHODE ISLAND.

DESIGN FOR PLASTER CAST.

Specification forming part of Design No. 6,741, dated Ju'y 1, 1873; application filed June 16, 1873.

To all whom it may concern:

Be it known that I, FREDERICK S. BATCHELLER, of the city and county of Providence, in the State of Rhode Island, have invented a Design for a Descending Dove, of which the following is a specification:

The nature of my design is fully represented in the accompanying photographic illustration, to which reference is made.

My invention consists of a design representing a dove in the act of descending, with

its wings and tail spread and its head bent forward, as shown in the accompanying illustrations, and is intended to be used as an ornamental design.

What I claim as my invention is—

The design representing a descending dove, substantially as herein described and shown.

FREDERICK S. BATCHELLER.
